Atty.

UNITED STATES PATENT OFFICE.

FRANK NOWAK, OF CHICAGO, ILLINOIS, ASSIGNOR OF ONE-THIRD TO SAMUEL N. POND, OF CHICAGO, ILLINOIS.

INDIAN-CLUB.

1,399,071.

Specification of Letters Patent.

Patented Dec. 6, 1921.

Application filed February 12, 1921. Serial No. 444,371.

To all whom it may concern:

Be it known that I, FRANK NOWAK, a citizen of the United States, residing at Chicago, in the county of Cook and State of Illinois, have invented certain new and useful Improvements in Indian-Clubs, of which the following is a specification.

This invention relates to Indian clubs, and has reference more particularly to that type 10 of Indian club which is designed to present a factor of safety in its use by having a transversely elastic yieldable body which softens and cushions any accidental blow delivered by the club. Persons not particularly skilled in the use of these clubs not infrequently injure themselves and others by accidental blows, and it is evident that an Indian club possessing a structure such that the injurious results of such blows are 20 avoided or minimized is a desirable article from the viewpoint of safety.

Indian clubs having a hollow rubber body portion designed to be inflated with air have heretofore been proposed, and also clubs 25 formed with a steel skeleton frame having a covering of canvas or rubber for cushioning purposes have also been proposed; but such clubs involve a considerably greater expense to manufacture than the standard wooden 30 club, and are too light in weight relatively to their size to possess the practical value as calisthenic devices of standard wooden clubs.

The main object of this invention is to provide a cushioned Indian club which shall 35 involve in its manufacture but slightly greater expense than the standard wooden club, which may preserve substantially the same weight, relatively to its size, as the standard wooden club, and which may be 40 made from the same stock as the standard wooden club. Another object is to provide an improved Indian club of the character specified wherein the center of gravity may be located nearer the lower or foot end of the 45 club.

With these and other objects which will be apparent from the following detailed description in view, my invention consists in the improved Indian club having the novel 50 structural features hereinafter described and more particularly pointed out in the claims.

In the accompanying drawings I have illustrated a practical and preferred embodiment of the invention, in which

55 Figure 1 is a side elevation of the club,

with the handle broken out between its ends; and

Fig. 2 is an axial longitudinal section of the same.

Referring to the drawing, 5 designates the 60 handle, 6 the knob on the outer end of the handle and 7 the lower end portion of the club, these parts or portions of the club being identical with the corresponding parts or portions of the standard wooden club. 65 The intermediate or body portion of the club is turned down in a lathe to form a narrow axial spindle 8 and a pair of annular shoulders 9 and 10 on the inner ends of the handle 5 and foot portion 7. Completely enveloping the spindle 8 is an envelop or shell 11 preferably made either of solid or canvas-reinforced rubber. This envelop or shell takes the general truncated oval form or contour of the cut away portion of the club 75 and at its ends is mounted and supported on the annular shoulders 9 and 10, to which latter it may be cemented if desired, although this is not necessary, since the natural elasticity of the rubber is sufficient to 80 maintain its snug fit on the shoulders, except when it is distorted by compression, the reaction or rebound at once restoring the snug fit of the parts.

When the rubber shell is compressed by a 85 blow, some of the confined air tends to escape around the end seats; and the rebound or return of the rubber to its normal form may be facilitated by providing a small air vent 12 through the rubber shell, although 90 this feature is not at all necessary to the practical utility of the device, and may be omitted. The walls of the rubber shell 11 are of substantial thickness, amply sufficient to maintain the form of the shell, in the normal use of the club, without requiring inflation or other internal support.

To compensate for the weight of the material eliminated by turning down the body of the club, I preferably provide in the base 7 100 of the club a socket 13 into which is forced an insert 14 preferably of lead; this insert having substantially the weight of the wood displaced in forming the chamber in the body of the club and the socket 13, less the 105 weight of the rubber shell 11. The use of this metal insert is, of course, optional; but it is preferred, since it both maintains the standard weight of a wooden club of the same size, and also transfers its center of 110

gravity to a somewhat lower point, which facilitates greater dexterity and ease in the manipulation of the clubs.

The advantages of this club, from the view point of safety, are manifest. If the user accidentally strikes himself or another, or even an object of furniture, with the body portion of the club, the elastic shell or envelop 11 effectively cushions the blow, even though the blow be sufficiently vigorous to depress the envelop into contact with the spindle 8, since in the latter event the transverse elasticity of the rubber alone is sufficient to prevent contusions or more serious injury.

I claim:

1. An Indian club having wooden handle and foot portions, an axial spindle connecting said handle and foot portions, and a hollow transversely resilient envelop or shell of sufficient thickness to maintain its form without internal support mounted at its

ends upon the said handle and foot portions and encircling said spindle and forming the main body portion of the club.

25

2. An Indian club having wooden handle and foot portions formed with annular shoulders on their inner ends, and an integral axial spindle connecting said handle and foot portions, and a hollow transversely resilient envelop or shell of truncated oval form and of sufficient thickness to maintain its form without internal support mounted at its ends upon said shoulders and encircling said spindle.

30

3. An Indian club having wooden handle and foot portions formed with annular shoulders on their inner ends and an integral axial spindle connecting said handle and foot portions, a hollow rubber envelop or shell of truncated oval form mounted at its ends upon said shoulders and encircling said spindle, and a metal insert in said foot portion.

40

FRANK NOWAK.
